UNITED STATES PATENT OFFICE.

GEORGE C. BECK, OF SPOKANE, WASHINGTON.

RING EXPANDER.

Application filed August 29, 1924. Serial No. 734,942.

To all whom it may concern:

Be it known that I, GEORGE C. BECK, a citizen of the United States, residing at Spokane, in the county of Spokane and State of Washington, have invented new and useful Improvements in Ring Expanders, of which the following is a specification.

The object of this invention is to provide a novel form of ring expander for expanding piston rings against the cylinder walls.

The prevailing expander now in use consists of a crimped strip of clock spring steel, the crimped portions being uniform in size and the apices of the crimped portion being relatively sharply bent. This crimped strip is disposed in the piston groove between the base of the latter and the piston ring. In use, the circular crimped strip is under tension and the alternately disposed and oppositely facing crimped portions, at their apices, engage the inner face of the ring and the periphery of the groove base and normally act to expand the ring against the cylinder walls.

As the average clearance between the ring and groove base is only twenty one thousandths of an inch, it has been the practice to use clock spring steel of an extremely thin gage. By reason of the sharply bent apices, engaging the ring and groove, these expanders quickly wore out, the main reason being that wear was intensively localized on the sharply bent apices of the necessarily thin steel.

It is the object of my invention to employ a much greater length of the spring strip for bearing engagement against the ring and groove base thereby greatly prolonging the life of the expander.

Another feature consists in utilizing the greater portion of the strip for bearing purposes, and a minor part for connecting the bearing or engaging portions with each other whereby the expander will more efficiently force the ring against the cylinder walls.

A further feature consists in shaping or crimping the strip in a manner to strengthen the resulting expander without employing a greater thickness of steel than is now in use.

A further object is to insure abutting engagement of the curved surfaces of the ring and groove throughout the entire length of the engaging portions of the strip.

My invention resides in the crimped strip,

as an article of manufacture, and also in the combination of the strip expander with a piston and ring.

Other features and objects of my invention will be more fully described in connection with the accompanying drawing and will be more particularly pointed out in and by the appended claims.

In the drawings:—

Fig. 1, is a view in side elevation of a completed strip shown on a very large scale.

Fig. 2, is an edge view of the same.

Fig. 3, is an enlarged horizontal sectional view of a piston, taken through a groove thereof, and showing my improved expander in position between a ring and the base of the ring groove in the piston.

Like characters of reference designate similar parts throughout the different figures of the drawing.

The device of my invention is designated as a whole at 1, and the same is made up from a strip of clockspring steel, initially flat. Either before or after tempering, I shape the strip 1 in a manner to carry out the features of my invention.

In the most preferred form, the strip 1 is crimped or shaped to provide alternately disposed elongated engaging sections 2 and 3, the former, as shown, engaging the inner face 4, of a piston ring 5, and the latter engaging the base 6 of a ring groove in a piston 7. One side wall of the groove is indicated at 8. It will be noted that the sections 2 and 3 are oppositely facing and preferably of equal length. The sections 2 and 3 are united by relatively short connecting sections 9.

Thus it will be seen that a major portion of the strip is utilized to form the sections 2 and 3, and a comparatively minor portion forms the connecting sections 9, hence, I have a preponderance of the strip arranged to sustain wear.

I preferably take advantage of the short connecting sections 9, to render the expander stronger without employing a thicker steel, and one way to accomplish this feature is to somewhat sharply bend the strip as at 10 and 11, at the junctures of said connecting sections 9 with the engaging sections 2 and 3. This, together with the relatively short length of the sections 9, with respect to the length of sections 2 or 3, not only serves to stiffen sections 9, but also serves to stiffen the sections 2 and 3 along their endmost por-

tions approximately as indicated by arrows 12 and 13. Consequently, the central portions 14 and 15 will be correspondingly weaker than the endmost portions of said sections 2 and 3.

In addition to the foregoing structure and advantages, it is a very great desideratum of my invention to obtain such uniformity and continuity of engagement that the elongated engaging sections 2 and 3 will perform their office in the most efficient manner, thereby prolonging the life of the expander.

In shaping the strip, I convexly arch the sections 2 and 3 on radii much shorter than the radii of the inner face 4, of the ring 5, and also shorter than the radii of base 6, of the piston groove. As will be clearly seen in Fig. 2, the sections 2 and 3 are arched to present convex faces toward the surfaces they are designed to engage. Now when these sections 2 and 3 are under load, as when the ring 5 is in place against a cylinder, these sections 2 and 3 flatten out and are under compression such as to not only 25 make their engagement continuous with the length of their respective surfaces, but also, to make such engagement of substantially uniform pressure throughout the length of the sections 2 and 3, thereby presenting large 30 area and long wearing surfaces. By reference to Fig. 3, it will be clear that sections 2 and 3 are in continuous engagement throughout their length with their respective surfaces, namely 4 and 6. Thus, while the 35 central portions 14 and 15 are initially or normally weaker than the endmost portions 12 and 13, before the expander is placed under load, this flattening of the arches to abutment against the surfaces of greater 40 radii, serves to place the entire length of each elongated section 2 and 3, under tension. When the strip is bent to circular form and disposed in the groove, the radially outwardly facing sections 2, are thereby 45 arched even more than is indicated in Fig. 2, before the strip 1 is bent, which is an advantage.

It will be noted that the sections 9, are not disposed on radial lines with respect to the 50 piston 7, but on the contrary, are in diverging relation. Hence, it will be clear that on compression of the expander by the ring 5, the entire expander can spread circumferentially in the groove, if necessary, to 55 compensate for any probable contraction of the ring 5. As it is usual not to bring the ends of the expander in actual contact, such circumferential contraction of the expander would not result in interference of the ends.

It has been stated that sharp bends are 60 objectionable but it will be clear that the relatively sharp bends 10 and 11 are so disposed with respect to the engaging sections 65 that no localized wear can be concentrated thereon.

It is believed that the device of my invention will be fully understood from the foregoing description, and while I have shown and described one specific embodiment of my invention, I do not wish to be limited thereto except for such limitations as the claims may import.

I claim:

1. A ring expander adapted to be disposed between the base of a piston groove and the ring therein, comprising a spring metal strip bent to form alternately disposed and relatively elongated ring and groove engaging sections and a relatively short supporting section between the ring and groove sections.

2. A ring expander adapted to be disposed between the base of a piston groove and the ring therein, comprising a spring metal strip shaped to form alternately disposed and oppositely facing elongated ring and groove engaging sections, said strip having relatively short supporting sections between the ring and groove sections.

3. A ring expander adapted to be disposed between the base of a piston groove and the ring therein, comprising a spring strip shaped to form alternately disposed and relatively weak elongated ring and groove engaging sections, and said strip having a relatively short and strong supporting section between the ring and groove engaging sections.

4. A ring expander adapted to be disposed between the base of a piston groove and the ring therein, comprising, a spring strip shaped to form relatively weak ring and groove engaging sections and a relatively strong supporting section between the ring and groove engaging sections.

5. A ring expander adapted to be disposed between the base of a piston groove and the ring therein, comprising, a spring strip having convex groove and ring engaging sections normally arched on shorter radii than the radii of the groove and ring surfaces engaged thereby and adapted to flatten under load to the radii of the surfaces engaged thereby.

6. A ring expander adapted to be disposed between the base of a piston groove and the ring held therein, comprising, a spring strip of uniform cross section bent to form relatively elongated oppositely facing and alternately disposed ring and groove engaging sections, the connecting strip portions intermediate said sections being relatively short and bent at relatively sharp angles at their junctures with said sections thereby rendering said connecting portions relatively stiff to form supporting sections for said elongated sections and stiffen the latter near their endmost portions, whereby the central portions of said elongated sections will the more readily flex,

said elongated sections being normally arched on shorter radii than the radii of the groove and ring surfaces engaged thereby and adapted to flatten under load to the radii of the surfaces engaged thereby, to insure a greater area contact of said elongated sections with their ring and groove faces.

7. A ring expander adapted to be disposed between the base of a piston groove and the ring therein, comprising, a strip shaped to form relatively elongated ring and groove engaging sections and relatively short connecting sections, whereby the major portion of the strip will be in engagement with the ring and groove surfaces.

8. In combination, a piston having a groove and a ring therein, and a ring expander between the base of said groove and said ring and provided with a series of elongated bearing sections engaging said ring and a series of like elongated bearing sections the base of said groove, said bearing sections constituting a preponderence of

the material of which said expander is formed.

9. A ring expander adapted to be disposed between the base of a piston groove and the ring therein, comprising a strip-like expander having elongated ring and groove engaging sections connected by relatively short supporting sections, said supporting sections being disposed on lines diverging from the radii of the piston.

10. A ring expander adapted to be disposed between the base of a piston groove and the ring therein, comprising a resilient strip of uniform cross section having elongated ring and groove engaging sections stiffened near their endmost portions and connected by supporting sections, the said engaging sections being arched on lesser radii than the radii of the surfaces engaged thereby to flatten into continuous engagement with such surfaces under load.

In testimony that I claim the foregoing as my own, I hereby affix my signature.

GEORGE C. BECK.
